Cone, deceased

Application January 28, 1935, Serial No. 3,765

24 Claims.

(Cl. 29—37)

This invention relates to automatic lathes and more particularly to lathes of the multi-spindle type. It has for an object to produce a machine capable of very high speed. To this end it is provided with means for cushioning the stopping of various parts, which, when moved, travel at high speed. As applied to a multi-spindle machine it also provides for improved carrier means for the stock by which the stock may be moved from one to a succeeding tooling station with great rapidity and with a minimum of noise, vibration and wear on the stock and its carrying parts at all times.

A further object is to improve the tool-carrying members, the stock feeding and holding mechanism and various other parts such that accurate high speed automatic functioning is facilitated.

A further object is to provide constructions facilitating changing of the machine set-up for different tooling operations whereby a minimum disorganization of the machine is necessary for this purpose.

Still another object is to provide a warning to the operator in case of heavy over-load on the machine.

Further objects and advantages will appear from a more complete description of an embodiment thereof shown in the accompanying drawings in which

Figure 1 is a front elevation of a multi-spindle machine constructed in accordance with this invention.

Figures 2 and 3 are left and right end elevations, respectively, of the same embodying the stock reel.

Figure 4 is a detail section on the line 4—4 of Figure 2.

Figure 5 is a top plan of the machine.

Figure 5a is a detail section on the line 5a—5a of Figure 5.

Figure 6 is a central diagonal section to a larger scale through the stock reel.

Figure 7 is a detail section to a larger scale on line 7—7 of Figure 3.

Figures 8 to 10, inclusive, 12 and 13 are detail sections on the correspondingly numbered section lines of Figure 7.

Figure 11 is a detail section on the line 11—11 of Figure 10.

Figures 14 and 15 are detail front and end elevations, respectively, Figure 15 being partly broken away showing tool slide limit mechanisms.

Figures 16 and 17 are detail sections on the correspondingly numbered section lines of Figures 14 and 13, respectively.

Figure 18 is a detail section on the line 18—18 of Figure 8.

Figure 19 is a detail section on the line 19—19 of Figure 7.

Referring to the drawings, at 1 is indicated a machine bed. Standards 2 and 3 extend upward-

ly from this bed adjacent to opposite ends and support thereon a frame member 4 which is arranged substantially parallel to the top face of the bed 1, being spaced thereabove and extending therealong.

Work holder and driving mechanism

Within the frame of standard 2 is positioned a turret or drum 5 which supports a plurality of work holders indicated generally at 6. This drum, as shown best in Figure 7, comprises a spider 10 having end plates 11 and 12 and an intermediate lateral partition 13, these parts being journaled at their peripheries within bearing members 14, 15 and 16 which are substantially rectangular in outline and are enclosed by the wall portions of the standard 2 and the angle connecting members 17, 18, 19 and 20. The work holders 6 are journaled in the partitions 12 and 13 and may be formed substantially like the work holders shown in my Patent No. 1,271,540. Four of such work holders are shown, though there might be more or less as desired, and they are arranged in circular series in substantially parallel relation about the axis of rotation of the drum 5. This drum is provided with an axial opening in which is journaled a shaft 25 which has a gear 26 fixed thereon meshing with gears such as 27 fixed to each of the work holders 6, so that as the shaft 25 is rotated all the work holders are turned simultaneously. The shaft 25 is coupled to a shaft 30 which extends lengthwise of the machine and has a portion 31 journaled in a bearing 32 in the inner end plate 33 of the standard 3. Within this standard 3 the shaft 30 has fixed thereon a link belt gear 34 and also a narrower link belt gear 35 inwardly of the end bearing member 36. The gear 34 is connected through a link belt 37 (see Figure 8) with a driving gear 38 fixed to a shaft 39. As shown best in Figure 18, the shaft 39, inwardly of the end wall 33 has fixed thereto a gear 40 which meshes with a similar gear 41 fixed to a drive shaft 42. This drive shaft extends entirely through the standard 3 and outwardly of the end plate 34 of this standard it may have secured thereto suitable means such as a pulley 45 (Figures 1, 2 and 3) by which this shaft 42 may be driven from a motor 46 or other suitable source of power. By this means the various work holders in the drum are caused to rotate during the normal operation of the machine.

Tool carriers and control mechanism

Between the frame 4 and the bed 1 are arranged slides for carrying tools in position to operate on work carried by the several holders mounted in the work-holding drum. Certain of these tools may be carried by a slide 50 mounted for movement parallel to the axes of the work holders and supported on the upper face of the bed 1. There

may also be one or more upper tool carrier slides such as 51 (see Figures 1, 7 and 9) which are mounted for sliding movement on one or more guide bars 52 supported in a bracket 53 secured to the lower face of the frame member 4 and in the end member 57. In order to hold these slides 51 against rotation, they may be provided with guide portions 54 engaging about a squared central guide bar 55 along which they may slide. The squared bar 55 is also carried by the bracket 53, as best shown in Figure 7. The slides 51 have elements 60 journaled therein through which pass adjustable links 62 pivoted at any selected of three points within slots in the lower portions of actuating arms 64. These actuating arms are fulcrumed, as on the pins 65 supported from the frame 4, and their upper ends are provided with cam follower rolls 66 which are actuated by suitable cams 67 (Figure 7) on a cam drum 70, the actuation of which will be later described. The slide 50 is connected through a link 75 pivoted thereto at 76 to a rock arm 77 (Figures 5 and 9). This rock arm is of general U shape and is pivoted at its upper and lower ends on a pivot shaft 78 journaled in upper and lower bearings 79 and 80. The upper arm member 81 carries a cam follower roll 82 which is actuated by suitable cams 83 (Figure 7) also secured to the cam drum 70.

In order that the lower slide 50 may be moved backward and forward at the high speed essential for a high speed machine, provision is made for cushioning its motion adjacent to opposite ends of its stroke. As shown in Figure 7, this means comprises a dash pot cylinder 85 suitably secured on the bed 1 and within which rides an elongated piston 86, the reduced extremity 87 of which is secured as by threading into the block member 88 secured to the pivot pin 76, as by the set screw 89. The opposite end of the cylinder 85 from that through which the stem 87 extends may be closed off by means of a tapered threaded plug 90. The piston 86 is of sufficiently loose fit within its cylinder so that air compressed between the piston 86 and the head end 88 of the cylinder may escape therewith when the piston moves toward the head 90 and so that air may pass in from the opposite end of the cylinder past the piston 86 when the air between the piston and the head 90 becomes rarefied by motion of the piston 86 outwardly. The clearance between the piston and the cylinder is so proportioned as to produce the desired cushioning effect for the tool slide 50 and the parts carried thereby. Any suitable tools (not shown) which it is desired to employ may be mounted on this slide 50 and these may operate on one or both of the pieces of stock carried by the work holders at the two lowest stations of the work holder drum.

The first station where the first tooling operations are done in the work is the rear lower station, from which the work is indexed to the forward lower station, then to the forward upper station, and then to the rearward upper station, where the finished work is cut off and the stock 65 is fed forwardly for a succeeding set of cutting operations.

Similar dash pot mechanisms for cushioning the motion of the upper slide or slides 51 may be employed, the attachments of the pistons to the slides being indicated on Figure 9 at 95.

Beside these two holders which operate substantially parallel to the axes of the work holders, other tool carriers may be employed which move in from front and back transversely to the 75 direction of these axes and from and toward the

central diametrical plane of the work holding drum. Such tool carriers are shown in Figures 9 and 10 at 100, 101, working inwardly from the front face of the machine and at 102 and 103 working in from the back face of the machine, these slides being mounted on front and rear slideway members 105 and 106, respectively. Each of these slides is arranged to support a tool carrier such as 110 having a tool 111 secured at its forward end and held in position by the pivoted strap elements 112 which may be turned to release or secure the holders 110 in position.

These slides 100 and 101 are arranged to be moved in and out by front controlling mechanism shown in detail in Figures 10 and 11. This mechanism comprises a rock shaft 120 having pinned to its upper end a hub member 121 integral with an actuating arm 122. Also keyed to the shaft 120 near its lower end is a hub member 123 having a forked arm 124 between the sides of which is pivoted on the pin 125 a link 126. The outer end of this link is pivoted as at 127 (see Figure 10) to a threaded bar 128 adjustably secured to the end wall member 129 of the tool slide 101. Beneath the collar 121 the rock shaft 120 has 25 journaled thereon a sleeve 130. This sleeve is supported on and is journaled in a cross frame member 131, and beneath this frame member it has clamped and keyed thereto a split collar 132 having a bifurcated arm 133 integral therewith. Between the sides of this arm 133 is pivoted a link 134 the opposite end of which is pivoted within the forked extremity of a bar 135 having a threaded portion 136 adjustably secured to the outer end wall 137 of the slide 100. Above the frame member 131, the sleeve 130 is provided with an actuating arm 140. Rocking of the arm 122 thus is caused to move the lower slide 101 in and out and rocking of the arm 140 moves the upper slide 100. Similarly the rear tool slides 102 and 103 are actuated by rocking of arms 150 and 152 at the rear of the machine, these being connected to the upper and lower tool slides 102 and 103 similarly to the connections to the upper tool slides 100 and 101. The arms 122, 140 and 45 150 and 152 are bifurcated for the reception of actuating links 155, 156, 157 and 158, respectively.

As best shown in Figure 5, the link 156 extends to a cam follower slide 160 having a cam follower 161 cooperating with suitable cams 1610 (Figure 7) on a cam drum 162. The link 155 extends to a similar cam follower slide 163 carrying a cam follower 164 cooperating with cams 1640 (Figure 7) on the cam drum 70. The rear link 158 is attached to the follower slide 165 carrying a cam follower 166 to be actuated by cams 1660 on the drum 162 and the link 157 is attached to a follower slide 170 having a cam follower 171 controlled by cams 1710 on the cam drum 70.

The limits of motion of the slides 100 and 103 toward the work are individually determined for each indexed position of the work holder drum. This is accomplished by means shown best in Figures 14 to 16. Referring to these figures, at 180 is shown a link pivoted at its upper end to an arm 181 carried by a rock shaft 182. This link 180 carries a pair of headed stop elements 183, the upper of which cooperates successively with 70 adjustable stop screws 184 threaded through a bracket arm 185 secured as by screws 186 to the top tool slide 100. A lower stop element 183 carried by the bar 180 is positioned to cooperate with a similar set of adjustable stop screws 188 carried 75

by a bracket 189 secured as by bolts 190 to the lower tool slide 101. There are as many stops 184 and 188 as there are stations for the work. Four stations being shown herein, there are likewise four each of the stops 184 and 188, which are adjustable independently of each other. The bar 188 rests on its rear face directly against the outer face of the supporting standard 2 so that the stops 183 form a rigid abutment limiting the inward motion of the tool slides 100 and 101 as the adjustable stops 184 and 188, positioned opposite thereto, impinge thereon, and provision is made by which the stops 183 are brought successively into cooperative relation to the adjustable stop elements 184 and 188. To this end the shaft 182, which extends from front to back of the machine, carries intermediate its length a relatively short cam follower arm 195 which rests upon any of a series of segmental cam elements 196 (see Figures 7, 12 and 14) secured to the periphery of the work holder drum. Since this machine is intended to operate at high speed, these cam segments 196 are arranged of gradually tapering thickness so that the arm 190 is moved gradually from one to another of its positions, with the stops 183 in operative relation to one or another of the adjustable stops 184 and 188, during substantially the entire period of time of the indexing of the drum from one to a succeeding angular position. At the opposite end of the rock shaft 182 a bar 180 similar to that shown in Figure 14 is employed for cooperation with stops 197 and 198 (see Figure 10) similar to the stops 184 to 188 for limiting inward motion of the tool carriers 102 and 103. With this arrangement there is no sudden motion of the parts necessary to adjust the cooperating stops for successive indexed positions.

Also because of the high speed at which this machine is intended to operate, means are provided for cushioning the motions of the tool carriers 100 to 103, inclusive, in both directions. One of such means is illustrated in detail in Figure 16. The brackets such as 185 and 189, which carry the adjustable stop screws such as 184 or 188, are extended beyond the stop screws and through the extension is threaded a sleeve 200. Through this sleeve is slidably a rod 201 having a head 202 at its inner end, this head riding in a socket opening 203 which may be drilled into a fixed frame portion 204. The outer end of this socket is counterbored and threaded for the reception of the inner threaded end of a sleeve 205 provided with a shoulder portion 206 limiting its entry into the socket. Its outer end is partially closed as at 207 to slidably engage the inner unthreaded extremity 208 of the sleeve 200, which extremity within the sleeve 205 forms an abutment for a ring member 209 through which the rod 208 is slidable. A spring 210 engages between the ring 209 and the head 202 of the rod 201. As the tool slide moves inwardly to bring one of the adjustable abutment screws 188 against the abutment 183, the inner end of the sleeve 20, pressing against the ring 209 compresses the spring 203 between it and the head 202, thus effecting a cushioning movement. As the tool slide moves outwardly the head of the sleeve 200 impinges on an adjustable abutment nut 211 threaded on the outer end of the rod 201 and held in an adjusted position by a lock nut 212 thereon, moving the rod 201 outwardly and causing the spring 210 to be compressed between the head 202 and the ring 209, which is held from outward movement as soon as it impinges against the in-turned outer end of the sleeve 206. This action cushions the last por-

tion of the motion of the tool slide outwardly. Such a mechanism is employed for each of the tool slides 100 to 103.

The cam drums 70 and 162 are shown as mounted for rotation with a cam shaft 220 which is journaled in suitable bearings 221, 222, 223 and 224 on the upper face of the frame member 4, and thus on the outside of the machine, the top portions of these bearings being formed by members separate from the frame and secured thereto by suitable bolts so that by the mere removal of these top bearing members the shaft 220 with the mechanisms carried thereby can be lifted off from the machine without disturbing other parts. However, in order to facilitate the changing of the cam set-ups for various tooling operations, provision is made, in accordance with this invention, for detachably securing the drums to the shaft 220 so that it is unnecessary to remove the whole assembly of the drums and shaft in order to change the tooling set-up, it being only necessary to change drums on which the cams for the different set-ups are arranged and which can be removably secured in position without removing the shaft 220 or any of the other parts of the machine. To this end, each of the cam drums 70 and 162 is formed in segmental sections, two such sections being ordinarily sufficient, which may be clamped in position on the shaft 220. For example, as shown in Figure 7, the cam drum 162 may be provided with hub portions 230 and 231, each being formed with a portion integral with each segment of the drum. These hub portions are preferably set in from the end of the drum so that they do not increase the over-all length of the drum. Their outer faces are preferably tapered so as to cooperate with a mating taper on the inner face of the continuous clamping ring 233, 234 which may be passed over the outer ends of the segmental hub portions and moved inwardly to hold these portions in assembled relation. The rings 233 and 234 may be forced inwardly toward the larger diameter portions of the hub portions, as by tightening bolts 235, which extend through the rings 233 and 234 and have threaded engagement with adjacent outwardly directed flange portions 236 of the drum. The shaft 220 is preferably provided with a keyway for a key 237 and one of the segmental portions of the drum is likewise provided with a mating keyway 238 so that when the segmental portions of the drum are clamped in position, they are also secured against rotation relative to the shaft 220. The cam drum 70 is likewise shown as made in segmental sections which are secured together by the clamping rings 240 similarly to the rings 233 and 234 for the drum 162. By providing a plurality of such segmental drums the cam arrangements for various machine set-ups may be applied to such drums. Thus, when desired, those previously on the machine may be readily removed by removing the clamping rings from the hub portions, whereupon the segments of other cam drums may be engaged about the shaft 220, the clamping rings placed over their hub portions and the drum segments thus clamped in position on the shaft 220. By mounting the shaft 220 on the outside of the machine, the clamping rings for the cam drums are freely accessible for removal or replacement of the cam drums.

The shaft 220 is arranged to be rotated at either of two selected speeds. Means for driving this shaft will now be described. Keyed to this shaft is a sleeve 250 (Figures 7 and 19) on which is secured a collar 251. This collar carries, pref-

erably integral therewith, a relatively thin housing member comprising a disk portion 252 provided at its margin with an annular flange 253. The open side of this housing portion is arranged to face a worm gear 254, which is keyed to a sleeve 255 mounted on a bushing 256 on the sleeve 250. The sleeve 255 is provided with a hub portion 2560 bearing against a hub portion 257 on the sleeve 250. This hub portion 257, as shown in Figure 5a, is provided with a slot 258, in which is secured as by screws 259, a block 260, which in turn has a slot 261 for the reception of an end portion of a shear pin 262. This shear pin 262 extends across into a similar block 15 carried by the hub portion 256. Over one portion, as the hub portion 257, may be secured a segmental cap 265 (see Figure 5a) which holds the shear pin 262 in position. This shear pin couples the worm gear 254 in driving relation to 20 the sleeve 250 but should abnormal resistance be encountered to the rotation of the shaft 220, this shear pin 262 will be sheared off between the hub portions 256 and 257 so that the worm gear 254 may turn without rotating the shaft 220. 25 When this occurs a clapper 270 (Figure 19) fulcrumed on the pin 271 carried by the worm gear 254 is caused to be rotated around the collar 251, which, as shown in this figure, is provided with angularly spaced cam projections 272 which are 30 contacted by a cam follower 273 on the clapper 270. This causes a striker portion 275, carried by a leaf spring 276 secured to the clapper 270, to strike successive blows on the flange 253 which acts as a bell to warn the operator that the 35 shear pin has parted, so that he may stop the machine and replace the shear pin after correcting any abnormal conditions which caused the shearing of this pin.

This worm gear 254 is driven by a worm 280 keyed to a shaft 281 (Figures 7 and 8) arranged transversely of the machine and suitably journaled in the top frame member 3. At one end this shaft 281 has secured thereto a bevel gear 282. This beveled gear 282 is arranged to be 40 driven by a bevel gear 283 (see Figure 18) keyed to a sleeve 284 journaled on the shaft 42. It may be coupled for rotation from the shaft 42 by means of a friction ring clutch shown at 285, alternating rings of which are secured to an enlarged extension 286 of the sleeve 284. This 45 clutch is controlled by the axial motion of a collar 287 slidably keyed to the shaft 42 and shifted by rocking a shift arm 288, which carries a shifter fork 289 having its ends engaged in a peripheral groove 290 in the shifter collar 287. When the shifter collar is moved to release the 50 clutch 285, an arm 291 extended from the arm 288 and having an adjustable screw abutment 292, is turned to bring the abutment screw against 55 the outer face of a braking arm 295, which is fulcrumed on the rock shaft 296 which carries the shifter arm 288, so that this braking member 295 presses against the outer face of the extension 285 and stops the rotation of the sleeve 284 60 and the rotation of the worm shaft 281. The rock shaft 296 has an actuating handle 297 on its outer end and is connected through a curved yoke 2960 with a rock shaft 2961 in axial alignment with the shaft 296 and which carries an 65 actuating handle 2970 on its forward end. The clutch 285 may thus be manually controlled from either the front or back of the machine. It may also be controlled automatically, the yoke 2960 carrying a follower 298 with which cooperates 70 75 cams 2980 (Figure 7) on a cam drum 299 also

keyed to the cam shaft 220. This mechanism constitutes the high speed drive for the shaft 281.

The low speed drive of the shaft 281 is derived from the shaft 30 by which the work holders 6 are rotated as previously described. The gear 35 on this shaft 30 is connected to a similar gear 300 carried by a shaft 301 (see Figure 8) by a link belt 302. This shaft 301 carries a gear 303 which meshes with a gear 304 keyed to a shaft 305. 10 The shaft 305 has keyed thereto a worm 306 which meshes with a worm gear 307 journaled on the shaft 281 and coupled to an overrunning clutch shown as a roller clutch at 308. The overrunning clutch may be clutched to the shaft 15 281 by a clutch collar 309 slidably keyed to the shaft 281. When the high speed drive from the sleeve 284 is stopped by the opening of the clutch 285, and the collar 309 is in clutching position, the shaft 281 is driven through the overrunning 20 clutch 308 at a low speed from the train of gearing and the link belt drives previously described from the same primary drive shaft 42. The link belts 37 and 302 may be held in proper operative tension by the belt tightener shoes 310 and 311 25 shown in Figure 8. The shoe 310 is shown as formed integral with a rock arm 317 fulcrumed at 312 and having its opposite end provided with a threaded engagement with a tightening shaft 313 extending out through one side of the frame 30 portion 3 where it may be accessible for adjustment. The shoe 311 is pivotally mounted on one arm of a bell crank lever 315, the opposite arm of which is likewise provided with a suitable threaded engagement with an adjusting rod 316, 35 the outer end of which is accessible from the outside of the frame 4 on the opposite side of the machine. The clutch collar 309 may be moved along the shaft 281 into and out of clutching engagement with the overrunning clutch 308. 40 As shown this may be done by hand, the collar 309 being provided with a peripheral groove 318 in which rides the end portion of an arm 319 suitably secured to a vertical rock shaft 3120. This rock shaft extends above the housing 3130 45 which encloses the overrunning clutch and the clutch collar 309, and has fixed at its upper end a hand lever 3150 (Figures 5 and 8) by which it may be rocked.

Means may be provided for turning the cam 50 drum shaft 220 by hand so as to facilitate making adjustments and the like, and means are provided for this purpose actuatable from both the back and front of the machine. On the splined forward extremity of the shaft 281 is keyed a 55 hand wheel 316 for this purpose. At the back of the machine and in axial alignment with the shaft 281 is a shaft 320. The forward end of this shaft has keyed thereto a pinion 321 (see Figure 8) which meshes with the gear 283 on the shaft 60 42 with which also meshes the gear 282 on the shaft 281. Outwardly of the machine frame the shaft 320 has keyed thereto the hub 324 of a hand wheel 325 (see Figures 5 and 8). Turning 65 of this hand wheel 325, therefore, acts to rotate the shaft 281 and to turn the cam shaft 220.

Work holder control and actuation

Besides controlling the motions of the tool slides and the slow and fast speed drives for the 70 shaft 220, this shaft also carries means for indexing the work-holding turret, for locking this turret in indexed position, for moving into and out of position a stock stop for the fourth station on the machine by which the amount of 75

feed of the stock when a new cycle of machining operations is to be performed is determined, and for opening and closing the work holders and for feeding the stock.

5 The turret or work holder drum-locking mechanism is shown best in Figures 7 and 12. Referring to these figures, it will be noted that the drum or turret which carries the work holders is provided with sockets 350, each of which may 10 receive at suitable times the lower end of a locking pin 351. This locking pin is mounted slidably in guide members 352 and is normally pressed downwardly toward the work holder-carrying drum as by means of a pair of springs 15 353. These springs react between adjustable washers 354 held on the upper ends of guide rods 355 over which the springs are positioned by nuts 356 threaded on the upper ends of the rods. The lower ends of these rods 355 are secured 20 in the guide members 352, and the lower ends of the springs 353 bear on a cross member 357 secured to the upper end of the locking pin 351. This cross member 357 has suitable holes therein through which the rods 355 extend. The locking pin 351 is provided with a recess 360 within 25 which is engaged one arm of a lever 361 (Figure 7) fulcrumed at 362 between the guide members 352. The opposite end of this lever 361 may be depressed when the work holder-carrying drum is to be indexed by an edge cam 363 secured to the cam shaft 220. In order that this work-holding drum may be released manually a second cam 364 is journaled on the shaft 220 and is provided with a handle 365 by which it 30 may be turned, both these cams being in position to act upon the end of the lever 361, which is preferably provided with a cam follower collar 366 journaled thereon to avoid unnecessary friction. The weight of the handle 365 normally 35 holds the cam 364 in inoperative angular position. Adjacent to the cams 363 and 364 the cam shaft 220 is provided with a cam 368 for actuating the stock stop and which may act on a cam follower 370 on an arm 371 fulcrumed at 40 372 (Figure 10). The lower end of the arm 371 is connected through a link 374 pivoted thereto to an arm 375 keyed to a rock shaft 376. This rock shaft is threaded for axial adjustment thereon of the stock stop arm 380, which carries a stop 45 element 381, against which the stock being fed through the work holder at the fourth station may impinge when it is fed forwardly. This stop stock arm is rocked into position just before a feeding action of the stock and is then retracted out of the way into the position shown 50 in Figure 10, so that the tools may be in position to act on the work.

The stock-gripping means for the stock holders are shown as actuated by cams 400 on the cam 55 drum 162. These cams act on a follower roll 401 (see Figure 7) carried by a slide 402 mounted to move substantially parallel to the axis of the work-carrying drum. To this slide 402 is connected a block 403 which has lateral extensions 60 404 (see Figure 13) against which engage springs 405 surrounding a pair of rods 406. These springs normally urge the slide 402 to the right as seen in Figure 7 so that a depending lug 410 thereon is positioned for successive engagement between 65 a pair of spaced lugs 411 and 412 on a plurality of slides 413. Each slide 413 is mounted for movement axially of a bar 415 secured between the wall members 11 and 13 of the work-carrying drum adjacent to one of the work holders. 70 Each member 413 is provided with an arcuate

lug portion 420 which rides within a peripheral groove 425 in a spool member 426 movably axially of each work holder 6. This spool member engages between the locking fingers 427 and when pushed between these fingers acts to clamp the work in its respective work holder in the manner shown in my prior Patent No. 1,271,540, which has been previously mentioned. When the spool 10 426 is moved to the right out from between the fingers 427 the work is released.

When the work is thus released, which is done after the finished article has been cut off from the bar stock, the stock at that particular station is moved forward into contact with the stock shop. This actuation of the stock feed is produced by cams 430 on the drum 162 which act on a cam follower 431 (see Figure 5) on a rockable follower arm 432. This rocking motion is transmitted through a rock arm 433 to a bar 434, which is slidably through an opening in the lug 20 435 secured to a feed block member 436. This feed member is carried on the end of a bar 437 (see Figure 4) which is slidably guided in the machine frame substantially parallel to the axis of the work holder-carrying drum. The outer 25 end portion of the bar 434 is threaded, and between the lug 435 and nuts 438 threaded on its outer end is positioned a spring 439, through which pressure is exerted to move the block 436 in feeding direction when the cams 430 move the 30 follower 431 in feeding direction. A pair of nuts 440 threaded on bar 434 to the right of the lug 435 form an abutment which may strike positively against the lug 435 when the bar 434 is moved to the left to produce the retractive motion of the block 436. 35

As shown best in Figure 1, the arm 433 is provided with a plurality of posts 445 any of which a member 446 attached to the right hand end of the bar 434 may be engaged at will in order 40 to provide a ready adjustment of the throw of the bar 434 for any desired angular extent of rocking of the arm 433. The block 436 is provided with an extension 450 on which is fulcrumed at 451 a bell crank lever 452. One arm 45 of this bell crank lever 453 is formed as a shaft on which is journaled a tapered roller 454 provided with a peripheral groove 455 which may be engaged over a circular head 456 of any one of the work holder feed members 457 which may be presented thereto as the work-holding drum is indexed, so that on movement to the right of the block 436 that one of the work holders which is in the No. 4 station may have its work feed element 457 actuated at the proper time to feed the stock therein. The other arm 460 of the bell crank lever 452 has passed therethrough a rod 461, which is secured to the outer end of the bar 437, and between it and a nut 462 threaded on the outer end of the rod 461, is positioned a coil spring 463. This coil spring normally urges the arm 460 against the outer end of a knurled hand wheel 464 also threaded on the rod 461 and actuatable by turning to retract the arm 460 and rock the roller 454 out of engagement with the 50 feeding head 456. When this is done this feeding head may be engaged and pulled outwardly, permitting a fresh piece of stock to be inserted in the work holder. When this has been done, the stock feeder is again placed in position and the hand wheel 464 screwed inwardly, whereupon the head 456 may be pushed to the right, engaging and riding along the tapered face of the roller 454 and ultimately latching into the groove 455. 55

In order to cushion the feeding motion because 60 70 75

of the high speed of operation of this machine, the block 436, as shown in Figure 4, may be provided with a socket 470 within which may ride a piston 471 having a reduced extremity 472 secured as by threading into a frame portion 473. This piston 471 fits sufficiently loosely into the socket 470 to act therewith as a dash pot, cushioning the movements of the block 436 and thus the feeding action on the stock.

10 In order to prevent the stock from being retracted during cutting operations thereon, as by those tools which are movable axially of the work, means may be provided for holding the work holders closed against the work at any desired of the several stations. Mechanism for doing this is shown best in Figures 13 and 17 and comprises an arcuate plate 474 having an arcuate rib 475 provided at its forward end with a tapering face 476. This plate 474 is secured as 15 by bolts 477 to the bearing portion 15 in position to engage the right hand face of the spool 426 of each work holder when it is in those stations where holding of the work securely is desirable. This prevents any untoward motion of the spool 426 in a direction to release the stock.

20 Indexing of the work-carrying drum to bring the several work holders successively into each operative station is also accomplished from the shaft 228. To this end it is shown as having secured thereto near the left hand end of the machine a gear 480 (see Figures 2 and 7). This gear meshes through an intermediate gear 481 with a gear 482. Turnable with the gear 482 is an indexing arm 483 having a follower roll 484 which may pass between guide flanges 485 of a Geneva motion wheel which may be integral with or secured to the end wall 11 of the work carrier drum.

Stock reel

40 In order that the stock extending to the various work holders may be supported and manipulated in the rapid manner desirable in a high speed machine, provision is made, in accordance with the present invention, to support this stock spaced back from the work holders in the drum and to turn this support as the drum is indexed and likewise to rotate the holders for such stock. This materially decreases the noise and wear both on the stock and on its carrying parts and facilitates the rapid handling of the stock. To these ends a pair of standards such as 500 and 501 for the stock may be provided as shown in Figures 1, 5 and 6. The standard nearest to the stock-holding drum may, if desired, be formed integral with the base of the machine, the standard 500 being so shown in Figure 1. The standard 500 is shown as having a circular opening in which is journaled substantially coaxially with the work-carrying drum, and as shown best in Figure 6, a disk member 502. This disk member, as shown, consists of a casing comprising a main portion 503 and a somewhat domed cover member 504 which are suitably secured together. The cover member 504 is connected to the end of the work-carrying drum, and as shown best in Figure 6, to the end wall member 11 thereof, by a tube 510. At one end this tube engages about a circular flange 511 on the cover 504 and at the other end about a tubular flange 512 of a collar 513 secured to the wall member 11 as by the studs 514. Thus as the work-carrying drum is indexed, the disk member 502 is also indexed correspondingly. The standard 501 has 55 journaled therein a disk member 520 coaxially

with the disk member 502 in the standard 500. In this member 502 and in the disk member 520 are bearings 521 and 522, respectively, arranged in circular series about the axis of rotation of these disk members, and journaled therein are 5 the stock-receiving tubes 525 through which the stock freely passes. Centrally the disk members 520 and 502 are connected for simultaneous indexing motion as by a tube connector 524. Between the disk member 503 and the casing closure 10 504, the tubes 525 have keyed thereto gears 526 which mesh with a central gear 527 on a shaft 528 journaled in a central bearing 529 in the disk member 502. This shaft 528 is also journaled in a bearing 530 in the collar 513, and an extension 531 of this shaft passes into the work holder-carrying drum and at its inner end is coupled as by the coupling 532 (see Figure 7) to the shaft 25 to be driven therefrom. Thus, as the work holders in the drum are rotated, so also 20 are the stock-carrying tubes 525 and as the work-carrying drum is indexed, so also are these supporting tubes indexed from one to a succeeding angular position.

25 From the foregoing description of an embodiment of this invention, it should be evident to those skilled in the art that various changes and modifications may be made without departing from the spirit or scope of this invention as defined by the appended claims.

30 I claim:

1. A machine of the class described, comprising a bed, a drum rotatable about its axis and carried by said bed, a plurality of holders arranged in circular series in said drum, a holder movable toward and from a drum-carried holder in one angular position thereof, means for indexing said drum to bring its holders successively into said angular position, stops limiting the approach of said movable holder toward a drum holder to 40 limit the approach of a tool carried by one of said holders to work carried by the other holder, and means operative to move said stops to present a selected stop into operative position for each indexed position of said drum, said stop presenting means including cams carried by said drum and extending substantially continuously from one to another of said drum carried holders, and a follower engaging said cam and controlling said stops, said cam being shaped to cause motion 45 of said follower to change from one to a succeeding stop to take place during substantially the entire indexing movement of said drum.

2. A machine of the class described, comprising a bed, a drum rotatable about its axis and carried by said bed, a plurality of holders arranged in circular series in said drum, a holder movable toward and from a drum-carried holder in one angular position thereof, means for indexing said drum to bring its holders successively into said 55 angular position, stops limiting the approach of said movable holder toward a drum holder to limit the approach of a tool carried by one of said holders to work carried by the other holder, means operative during substantially the entire 60 indexing movement of said drum moving said stops to present a selected stop into operative position for each indexed position of said drum, and means for cushioning the movement of said movable holder as it approaches said stopped 65 position as determined by any of said stops.

3. A machine of the class described, comprising a bed, a drum rotatable about its axis and carried by said bed, a plurality of holders arranged in circular series in said drum, a holder movable 70

- 5 toward and from a drum-carried holder in one angular position of the latter holder, means for indexing said drum to bring its holders successively into said one angular position, a stop for said movable holder for each of said drum holders, a movable member having a stop cooperating successively with the other of said stops to limit the motion of said movable holder at each indexed position of said drum, cam means carried by said drum and extending substantially continuously from one to another of said drum-carried holders, a rock shaft, a cam follower arm carried by said shaft in operative engagement with said cam means to rock said shaft from 10 one to a different angular position during substantially the entire period of each indexing movement, and operative connections between said rock shaft and member causing the stop carried by said member to be moved from cooperative relation to one of the other of said stops to another of said other stops as said drum is being indexed.
- 15 4. In combination, a rotary drum, a plurality of work holders for bar stock arranged in circular series in said drum, means for indexing said drum, a tool carrier movable substantially parallel to the axis of said drum, work-gripping means for each work holder, an actuating element for each gripping means movable axially of its respective holder to grip or release the work, means acting on said element when its work is in position to be operated upon by a tool on said carrier to hold said element in work-gripping position and thereby insure against slipping of 20 the stock under the thrust exerted thereon by said tool, and means with which each of said elements engages when its respective holder is in a different indexed position actuatable to release and then grip the stock.
- 25 5. In combination, a rotary drum, a plurality of rotary work holders for bar stock arranged in circular series in said drum, means for indexing said drum, work gripping means for each work holder rotatable therewith, an actuating element for each work gripping means carried by said drum and non-rotatable with its gripping means but movable axially of its holder, means cooperating with each of said elements at certain ones of the indexed positions of the corresponding work holder to hold said element against axial motion from its work-gripping position, and means cooperating with said element in another indexed position of the corresponding work holder to move said element axially to work-releasing 30 position.
- 35 6. In combination, a rotary drum, a plurality of rotary work holders for bar stock arranged in circular series in said drum, means for indexing said drum, work gripping means for each work holder rotatable therewith, an actuating element for each work gripping means carried by said drum and non-rotatable with its gripping means but movable axially of its holder, means cooperating with each of said elements at certain ones of the indexed positions of the corresponding work holder to hold said element against axial motion from its work-gripping position, and means cooperating with said element in another indexed position of the corresponding work holder to move said element axially to work-releasing position and then to return it to work-gripping position.
- 40 7. In combination, a rotary drum, a plurality of rotary work holders for bar stock arranged in circular series in said drum, means for indexing said drum, means for rotating said work holders, work-gripping means for each holder, an element rotatable with each holder and movable axially thereof for actuating said gripping means to grip and release the work, a member non-rotatable with each holder and movably carried by said drum operatively connected to each of said elements, means movable adjacent to one station of said holders and with which said members successively cooperate as said drum is indexed for 45 releasing and then gripping the work at said station, a tool carrier movable substantially parallel to the work holder in another of said stations, and a stationary element with which each of said members cooperates at said other station to hold said member in work-gripping position to prevent backward motion of the work due to the thrust thereon of a tool on said carrier.
- 50 8. In combination, a rotary work holder, a stock feeder rotatable with said holder and movable axially thereof to feed the stock, a member movable substantially parallel to said work holder axis, a lever fulcrumed on said member and having an arm normally in operative engagement with said feeder, means for moving said feeder, a threaded rod extending from said member, a hand wheel threaded on said rod and with which said lever may engage, and a spring pressing said lever against said rod.
- 55 9. In combination, a rotary work holder, a stock feeder rotatable with said holder and movable axially thereof to feed the stock, a member movable substantially parallel to said work holder axis, a lever fulcrumed on said member and having an arm normally in operative engagement with said feeder, means for moving said feeder, a threaded rod extending from said member, a hand wheel threaded on said rod and with which said lever may engage, and a spring pressing said lever against said rod, said spring being arranged to press said lever toward operative angular position.
- 60 10. In combination, a plurality of rotary work holders for bar stock, a stock support spaced from said holders, a rotary stock carrier for each holder on said support and through which the stock may freely extend, and means for effecting simultaneous rotation of said work holders and stock supports.
- 65 11. In combination, a rotary work holder for bar stock, a stock support spaced back from said holder, a rotary stock carrier carried by said support and through which the stock may freely extend, and means for simultaneously rotating said holder and carrier to rotate stock held by 70 said holder and extending into said carrier.
- 70 12. In combination, a rotary work holder for bar stock, a stock support spaced back from said holder, a rotary stock carrier carried by said support and through which the stock may freely extend, a rotary shaft, driving connections from said shaft to said holder and to said carrier, and means for rotating said shaft.
- 75 13. In combination, a plurality of rotatable work holders for bar stock arranged in circular series, a stock support spaced back from said holders, a plurality of rotary stock carriers carried by said support in circular series corresponding to said work holders and through which the stock may freely extend, and means for simultaneously rotating each holder and its respective carrier.
- 80 14. In combination, a plurality of rotatable work holders for bar stock arranged in circular series, a stock support spaced back from said 75

- holders, a plurality of rotary stock carriers carried by said support in circular series corresponding to said work holders and through which the stock may freely extend, a rotary shaft extending coaxially of said series of holders and carriers, driving connections from said shaft to said holders and carriers, and means for rotating said shaft.
15. In combination, a rotary drum, a plurality of rotary work holders for bar stock arranged in substantially parallel relation in said drum, means for turning said drum, a stock support spaced from said drum, a member rotatable substantially coaxially with said drum and carried by said support, rotary stock carriers carried by said member for supporting stock extending to said drum work holders, connections between said drum and member causing simultaneous turning motions thereof, and means actuatable to rotate said work holders and stock carriers.
16. In combination, a rotary drum, a plurality of rotary work holders for bar stock carried by said drum and arranged in circular series about the axis of rotation of said drum, means for turning said drum, a plurality of standards spaced from each other and from said drum, a member rotatably carried by each standard substantially coaxially with said drum, a plurality of tubes extending between and rotatably carried by said 30 members substantially coaxially with said work holders and forming supports for bar stock extending to said work holders, a connection between said drum and one of said members insuring simultaneous turning thereof, and means for rotating said work holders and tubes in unison.
17. In combination, a rotary drum, a plurality of rotary work holders for bar stock carried by said drum and arranged in circular series about the axis of rotation of said drum, means for turning said drum, a rotary shaft arranged coaxially of said drum, means for rotating said shaft, driving connections from said shaft for rotating said work holders, a pair of standards spaced apart and from said drum, a member rotatably carried by each standard substantially coaxially with said drum, a plurality of tubes extending between and rotatably carried by said members substantially coaxially with said work holders and forming supports for bar stock extending to said work 50 holders, means connecting one of said members to said drum to be turned thereby, a rotary shaft extending from said one member toward said drum, rotary driving connections between said last mentioned shaft and said tubes, and means coupling said shafts for simultaneous rotation.
18. In combination, work-holding mechanism, tool-holding mechanism, and means for moving said mechanisms relatively, said means comprising a rotary shaft, a cam drum secured to said shaft in an accessible position and cams carried by said drum, said cam drum being formed in sections, and means accessible while said shaft and drum are in normal operative positions for releasably securing said drum sections together and to said shaft, whereby said drum may be removed and another drum substituted therefor without removing said shaft from its normal position.
19. In combination, a bed, a frame extending along and above said bed, a rotary drum positioned between said bed and frame, a plurality of work holders arranged in circular series in said drum about its axis of rotation, tool holders lo-
- cated between said bed and frame and movable toward and from work carried by said work holders, a rotary shaft journaled in said frame, means actuated by the rotation of said shaft for indexing said drum, and means for controlling relative motions of said tool and work holders from the rotation of said shaft comprising a segmental cam-carrying drum, and means accessible while said shaft is in normal position for releasably securing the segments of said cam-carrying drum together and to said shaft.
20. In a machine of the class described, work-holding mechanism, tool-holding mechanism, means for moving said mechanisms relatively, means including a rotary shaft journaled on the outside of the machine, and a cam-carrying drum secured to said shaft for actuating said moving means, said drum being formed of segmental sections, each section having a segmental hub portion engageable with said shaft, and a ring engageable about said hub portions of the several sections for holding said sections about and secured to said shaft.
21. In a machine of the class described, work-holding mechanism, tool-holding mechanism, means for moving said mechanisms relatively, means including a rotary shaft journaled on the outside of the machine, and a cam-carrying drum secured to said shaft for actuating said moving means, said drum being formed of segmental sections, each section having a segmental hub portion engageable with said shaft, the outer faces of said hub portion being longitudinally tapered, a ring having a matingly tapered inner face engageable about said hub portions to hold said sections in assembled relation, and means for drawing said ring toward the larger diameter portions of said hub to exert clamping pressure thereon.
22. In combination, a plurality of relatively movable devices, a rotary shaft, mechanism actuated by said shaft for relatively moving said devices, a member fixed to said shaft, a member journaled on said shaft, a shear pin connecting said members, means for rotating said journaled member, and an alarm device actuated by relative rotation of said members as when said pin has been sheared.
23. In combination, a plurality of relatively movable devices, a rotary shaft, mechanism actuated by said shaft for relatively moving said devices, a member fixed to said shaft, a member journaled on said shaft, a shear pin connecting said members, means for rotating said journaled member, a shell element fixed to one of said members, a cam element carried by the other of said members, and a clapper actuatable on relative motion of said members to beat upon said shell and thereby signal upon the shearing of said pin.
24. In combination, a bed, a frame positioned above said bed, a pair of superposed slides between said frame and said bed, an upright shaft, a rock member journaled on said shaft and having a pair of arms, connections from one of said arms to the upper of said slides, an arm fixed to said shaft above said member, an arm fixed to said shaft below said member, connections from said last-mentioned arm to the lower of said slides, a rotary shaft, and cam mechanism actuated by said shaft and engaging the other arm of said member and the other arm fixed to said upright shaft.

FRANK L. CONE.
